GAS DETECTOR

Harry A. Dodge and Charles J. Dietrich, New
York, N. Y.

Application August 24, 1933, Serial No. 686,594

4 Claims. (Cl. 177—311)

This invention relates to means for automatically indicating in the form of audible, visual or other signal the presence of explosive gases, vapors or the like.

Our invention finds application for the automatic detection of explosive gases in mines or other localities, in the form of a system most advantageously of electrical type. However, our invention is not limited to the automatic detection 0 of gases, vapors and the like of explosive nature, and is useful in detecting gases, vapors and the like affecting generally a predetermined atmosphere.

In general our invention comprises a lamp or 5 other source of a flame, with which is combined thermostat means responsive to an elevation or depression of temperature, whereby to produce a signal either audible, visual or otherwise perceptible.

0 In greater particular, as applicable to an electrical type of system, such thermostat or other suitable means responsive to variation of temperature controls electrically actuated devices, usually including a relay, the arrangement being such 5 that upon variation of electric current arising from variation of temperature the signal is operated. The electrical circuit inclusive of the thermostat means is preferably of the closed circuit type, to thereby insure continuity of operative condition with which advantage is coupled 0 the additional safeguard that upon breaking or other substantial change in the detecting circuit, the signal is operated.

More preferred forms of our system are of such 5 nature that a plurality of unit assemblies, each unit including a lamp and thermostatic means, may be connected by common wiring. In the most preferred forms of the invention, a separate signal or group of signals is arranged for each 0 assembly unit, whereby the assembly unit affected by the presence of explosive or other deleterious gas, vapor or the like is selectively indicated.

Most advantageously, the thermostat means 5 comprises a set of thermostat elements individually respectively responsive to increase of temperature and to decrease of temperature, whereby under the condition of the presence of a gas of explosive nature, that is to say, tending to increase the temperature of the flame, the thermostat element responsive to increase of temperature effects the operation of the signal, and, similarly, upon the condition of decrease of temperature of the flame due to the presence of non-combustible or less combustible gas, vapor or the

like, the thermostat element responsive to decrease of temperature effects the operation of the signal.

Combined with our temperature responsive means, we provide a flame extinguishing means 5 whereby in the circumstance of use in a mine or other locality the presence of an explosive gas, vapor or the like entails the danger of explosion, or the danger of asphyxiation or other danger leading to irreparable or serious results. In systems embodying our flame extinguishing means, 10 the operation of the same is had additively to that of effecting and localizing the danger of the deleterious gas.

Further features and objects of the invention 15 will be more fully understood from the following detail description and the accompanying drawings, in which

Fig. 1 is a diagrammatic view of an electrical circuit arrangement, illustrating an embodiment 20 of our invention.

Fig. 2 is a detail diagrammatic view of certain parts at a certain operated stage.

Fig. 3 is a detail diagrammatic view corresponding 25 to Fig. 2 but showing another stage of operation.

Fig. 4 is a sectional view of one manner of assembly of a lamp and temperature variation responsive means; and

Fig. 5 is a plan view on the line 5—5 of Fig. 4. 30

Referring to the drawings, a typical lamp suitable for the purpose is indicated at 10. In the application of the invention to mines and other locations subject to the presence of inflammable gases, such lamp 10 is provided with suitable 35 means for minimizing explosion. A typical form of lamp for mines, pursuant to present practice, comprises a metal gauze above and completely surrounding the flame, to retard the passage of ignited gas through the gauze. The particulars 40 of preferred forms of the lamp, per se, are set forth hereinafter.

As is diagrammatically illustrated in Fig. 1, the lamp 10 is provided with a flame-extinguishing mechanism 11 of suitable arrangement which is 45 releasable in response to the presence within the region of the flame of gases, either explosive, asphyxiating or otherwise deleterious, affecting the flame either to increase or decrease its temperature. One such suitable arrangement is illustrated in Fig. 1, comprising a snuffer element 12, in the form of a cap, which cap may be of metal or other material, such as lava or the like, co-ordinated in an electrical system, in which arrangement the cap 12 may be attached to a lever 55

13, pivoted at 14 and either of or embodying a suitable section of magnetic material, for co-operation with an electromagnet 15 having a ferrous core 16.

5 Associated with the flame 10a of the lamp are suitably arranged thermostatic means responsive to increasing and decreasing temperatures of the flame. Advantageously, such temperature variation responsive means is in the form of a 10 thermostatic element 17 responsive to increase of the temperature and a thermostatic element 18 responsive to decrease of temperature.

One form of circuit arrangement of the above 15 stated parts and the desired signalling devices, as illustrated in Fig. 1, comprises a battery 19, which may be a storage battery, supplied with current by an automatic charger 20, energized from the power lines 21, 22.

A conductor 23 connects one end of the battery 20 19 with a conductor 24 leading to the thermostat elements, say, to one terminal 18a of the thermostat element 18, its other terminal 18b being connected by a conductor 25 to one end of the winding 15, the opposite end of the winding being 25 connected by a conductor 26 to a conductor 27. One terminal 17a of the thermostat element 17 is connected by a lead 28 to the terminal 18b of the thermostat element 18; its other terminal 17b is connected to a conductor 27.

30 The conductor 27 leads to the winding 30c of a relay 30, or other suitable device, for actuating the signal means. In the drawings we have indicated three forms of signals, to wit, an audible alarm 31 such as an electric bell or equivalent, a visual alarm such as an electric lamp 32, and semaphore 33 and/or equivalent.

The relay 30 is of the combined pivoted armature and solenoid type, having the pivoted armature 44 provided adjacent its free end with a 40 bridging member 63 adapted to engage with the contacts 35 and 36. Attached to the free end of the armature 44 is the semaphore 33 adapted to serve as a visual signal device. Associated with the armature 44 is a core 30a of magnetic material provided on its end with a piece of brass, copper, or other non-magnetic material 30b and which is interposed between the armature 44 and core 30a. Surrounding the core 30a is a coil 130, one end of which is connected to the conductor 45 27 and the other end to the conductor 32. Normally, current is passing through the coil 130 and therefore the armature 44 is attracted to the core 30a and the bridging member 63 is maintained out of engagement with the contacts 35 and 36. Gravity is ordinarily sufficient to cause the movement of the bridging member 63 into engagement with the contacts 35 and 36 upon failure of the circuit through the coil 130 or from 50 any other cause, though a spring 45 or equivalent device may be employed to ensure such action. Associated with the armature 44 and coil 130 is the solenoid 30c provided with a plunger armature 30f. To one end of the plunger armature 30f is attached one end of a spring 30g, the other end of this spring being attached to one end of an adjusting screw 30h that passes through a threaded hole in an abutment wall 30k. This adjusting screw 30h is provided with a check nut 30i for retaining the screw, and therefore the spring 30g, in adjusted position. The other end of the plunger armature 30f is in operative relation with respect to the armature 44. The solenoid 30c is connected one end to the conductor 27 and as 55 above described the other end to the conductor 70 75

32, and the solenoid 30c and coil 130 are arranged in parallel.

Normally the current from the conductor 27 to the conductor 32 flows through the solenoid 30c and coil 130 alike. The plunger armature 30f of the solenoid 30c is pulled into the solenoid against the spring 30g and toward the armature 44. The core 30a is magnetized and will hold the armature 44 against the non-magnetic member 30b. The pressure of the plunger armature 30f against the armature 44 is not sufficient, under the assumed conditions, to overcome the holding power of the coil 130. When, however, the current through the coil 130 and solenoid 30c is increased due to a short circuit or due to the operation of 10 thermostat 17 (which shunts out coil 15 and therefore increases the potential across the coil 130 and solenoid 30c) the attractive force of the coil 130 increases but the plunger armature 30f is pulled into the solenoid 30c with increased 20 strength, moving it at a rapid rate of speed against the armature 44 and with a sufficient momentum to break such armature 44 away from the core 30a, especially as the lever arm available to the plunger armature 30f is greater than 25 the lever arm available to the core 30a. The ease with which the armature 44 may be broken away from the core 30a is aided by the use of the non-magnetic member 30b interposed between the core 30a and the armature 44. 30

Assuming the flame 10a of the lamp to be burning under normal conditions and the atmosphere within the region of the flame to be normal, in which circumstance the thermostat element 18 is in its closed position and the thermostat element 17 is in its open position, and the flame-snuffer element 12 to be in its retracted position, the path of the circuit embodying the above-named parts is as follows:

Current source 19, conductor 23, conductor 24, 40 closed terminals of thermostat element 18, conductor 25, winding 15, conductor 26, conductor 27, coil 130 and solenoid 30c, conductor 32 to current source 19. The winding 15, being thus energized, retains the snuffer element 12 in its non-operative position. Also, under such circuit conditions, the solenoid 30c is energized to hold the armature 44 in its attracted position, whereby the semaphore 33 is in its elevated, i. e. non-indicating position and the aural and visual alarms 50 31 and 32 respectively are non-operated.

Assuming, now, the presence of an explosive gas within the region of the lamp flame 10a, or the presence of any gas tending to increase the temperature of the flame, such increase of flame 55 temperature effects the closure of the terminals of the thermostat element 17, under which conditions, the circuit is:

Current source 19, conductor 23, conductor 24, terminals of thermostat element 18, conductor 25, 60 winding 15, conductor 27, solenoid 30 and solenoid 30c, in parallel, conductor 32 to current source 19, under which circuit conditions, the winding 15 is sufficiently deenergized because of the short circuit between conductors 25 and 27 65 through thermostat element 17, thus releasing the snuffer element 12, whereby the flame 10a is extinguished.

Upon the extinguishing of the flame 10a as above described, the temperature within the device will become rapidly lowered resulting in the ultimate opening of the engagement between the elements of the thermostat 17 and also the opening of the engagement between the elements of the thermostat 18. Immediately the thermostat 75

18 is opened the resistance 43 is placed in the energizing circuit above described. Under such conditions the amount of current delivered to the windings 30 and 30c is lowered sufficiently to permit the energy of the spring 30g to overcome the attraction by the winding 30c of the plunger 30 which thereupon retracts or moves to the left as shown in Fig. 1, whereupon the spring 45 will be sufficient to move the armature 44 to the right so as to bring the contact plate 63 into engagement with the contacts 35 and 36. The retraction of the armature 44 moves the semaphore 33 into position to be observed. The engagement of the contact plate 63 with the contacts 35 completes two circuits one of which extends from a source of current 19, conductor 23, contact plate 63, contact 35, conductor 37, lamp 32, conductor 38, conductor 32 back to source of current 19. The lamp 32 is lighted. Also a circuit is closed from source of current 19, conductor 23, bridging contact 63, contact 36, conductors 39 and 40, audible signal 31, conductors 41 and 32 back to source of current 19.

To start the device in operation again, the operator will start the flame 10a and will manually move the armature 13 into engagement with the core surrounded by the winding 15. The thermostat 18 is made sensitive enough so that the terminals thereof will close immediately after the flame 10a is started in operation, and therefore the original energizing circuit above traced will be completed and the armature 13 held in position to hold the snuffing device 11 in the position shown in Fig. 1.

Assuming the presence of a gas within the region of the gas flame 10a, tending to decrease the temperature of the flame, the reduction of flame temperature effects the opening of the terminals of the thermostat element 18 (the terminals of the thermostat element 17 having been opened and remaining open) the circuit under such conditions, is:

Current source 19, conductor 23, resistance 43, winding 15, conductor 26, conductor 27, solenoid 30 and solenoid 30c in parallel, conductor 31, conductor 32, to current source 19. Under such circuit conditions, the reduction in current potential across the winding 15 and the solenoid 30c as in the above assumed circumstance, permits the withdrawal of the relay armature 44, accompanied by the actuation of the alarm or alarms, either mechanically and/or electrically, similarly as above set forth.

Under the circumstance of presence of a non-combustion supporting gas within the region of the lamp flame 10a, the winding 15 of the snuffer element 12, may be arranged either to effect the release of the snuffer element 12 to extinguish the flame 10a, or to retain the snuffer element 12 in its non-operative position, as may be desired.

The construction is such that in the circumstance of open circuit, the resulting drop of current potential across the terminals of the solenoid 30c brings about the actuation of the visual and/or aural alarms, as under the circumstances of flame temperature increasing and flame temperature decreasing conditions.

In the event of short circuit condition in the circuit, such condition effects similarly the energization of coil 130 to actuate the aural and/or visible alarms, accompanied by extinguishment of the lamp flame.

A system for detecting and alarm effecting for a plurality of detection locations may comprise individual circuit parts in duplicate of the above

described circuit parts, including individual visual and/or aural alarms selectively for such respective circuits.

Desirably, detection and alarms effecting for a plurality of detection locations, may be had by 5 circuit arrangement embodying common wiring. For example, in the embodiment illustrated in Fig. 1, in addition to the above described detection location of the lamp 10, a lamp 10' may be positioned at a location other than that of the 10 lamp 10. The parts associated with the lamp 10' are designated by like reference characters with a prime suffix. In addition to such like parts, there is the conductor 46 interconnecting the juncture 34' with the conductor 23. 15

For selective operation of the semaphore 33', lamp 32', or other visible indicator, like circuit and associated parts are employed, corresponding to the above circuit and associated parts, designated by like reference characters with a prime 20 suffix. In addition to these parts the conductor 47 connects the terminal of the solenoid 30c with the conductor 32. By such arrangement, the semaphores 33 and 33' are selectively operated 25 respectively upon detection at the locations 10, 10', and likewise the lamps or visible alarms 32 and 32'.

Also, as is illustrated in Fig. 1, the bell or other aural alarm 31 is actuated in common under the condition of detection of presence of an explosive or other flame temperature increasing gas or of a flame temperature decreasing gas at the stated locations 10 and 10', and similarly for any additional locations as may be desired. 30

It is understood that the bridging contact 63 35 and the associated contacts 35, 36, may be in the form of a so-called mercury switch, usually of pivotal type, the mercury functioning as the jointure contacting material. In such mercury type switch (not shown) the hollow body, usually 40 of glass, is rocked to and fro by direct or indirect connection with the relay armature 44, suitable linkage or other operating connections being provided for the mechanical actuation of the semaphore 33. 45

In the use of a common alarm or other indicator, such as the bell 31 or other aural device, say for a two lamp system, and assuming that detection of the presence of a flame temperature increasing or flame temperature decreasing gas 50 to be indicated, accompanied by the extinction of the lamp at the detected location, the system is rendered operative for detection and indication of the other lamp by the provision of the circuit arrangement illustrated in Figs. 2 and 3. 55

In the arrangement shown in Fig. 2, and also in Fig. 3, like parts are indicated by like reference characters, corresponding to Fig. 1. In addition, there are provided the supplemental parts, namely, the three-way switch 50 for alternately connecting the conductor 37 or the additional conductor 51 with the lead 38a for connection with the conductor 40. An additional contact is provided at the terminus of the conductor 51, namely the contact 52, positioned to 60 be engaged by the bridging contact 63 when the relay armature 63 is in its attracted position. Fig. 2 illustrates the setting of the movable contact arm 50a of the three-way switch 50 for interconnecting the contact 35, through conductor 70 65 31, lead 38a, with the conductor 40.

Assuming the detection of a flame temperature affecting gas at the location of the lamp 10, giving rise to the retraction of the relay armature 44 by its spring 45, to the alarm-indicating position, 75

as is illustrated in Fig. 3, the attendant upon observing such situation throws the movable contact arm 50a of the three-way switch from the indicated full line position to its indicated dot 5 and dash line position 50b, thus interrupting the circuit through the common alarm 31 with respect to the contact 35. When the trouble on this particular detecting circuit is cleared, armature 44 is attracted by its relay 30, which again causes 10 the signal 31 to sound, apprising the attendant of the changed condition. The attendant therefore operates the three-way switch 50 to bring the arm 50a thereof into engagement with the conductor 37, as indicated in Fig. 2.

15 The physical apparatus to be located at the various stations designed to be protected by our improved invention may take any form desired. In Figs. 4 and 5 there is shown one form of preferred apparatus, such form being adapted for 20 either stationary or portable use. Referring to such figures, 64 designates a tank or fuel font containing the liquid fuel 65. Through the upper end plate 66 of the font 64 extends the tubular member 10 through which passes the wick 68, 25 such wick extending into the body of the fuel 65. The wick 68 extends upwardly slightly beyond the upper end of the tubular member 10, and in a position to be engaged by the sparks generated by a mechanical lighting device 69 secured to the 30 upper face of the font end plate 66.

Secured to the upper face of the plate 66, by screw 70, is a bracket 71, in which may be adjustably secured the thermostats 17 and 18, the position of such thermostats 17 and 18 being such 35 that they are acted upon by the flame 10a, as above described with respect to Fig. 1. Leading from the thermostat 17 is a cable 72 containing the conductors 24 and 25, and leading from the thermostat 18 is the cable 73 containing the conductors 27 and 28.

Adjacent to the candle 10 and the bracket 71, and secured to the plate 66, is the electromagnet 15, having associated therewith the snuffer 12 and armature 16. Also on the plate 66 is secured the resistance 43. On the plate 66 and surrounding the assembly of elements just described, is a spider frame of metal including a lower ring plate 74 and an upper ring plate 75, in which frame is a cylindrical glass tube 76. Secured to the spider frame and thus to the font 64, is an upper frame 77, into which the thermostats 17 and 18 may extend. Within the upper frame 77 and forming a cover is a wire mesh screen 78.

55 The entire assembly thus conforms to a regulation miner's lamp. The various parts are readily disassembled to allow access to the devices within the glass tube 76, and to permit the operator to fill the font 64 and operate the mechanical lighting device 69.

Also mounted on the plate 66 is the coil or resistance 43.

The apparatus is adapted to rest on a support, or to be hung on a hook by means of the eye 79 secured to the top of the frame 77.

Our system may also be arranged to respond to the condition of short-circuit of the line, in 5 which circumstance the current through the relay winding is increased. To meet such condition the relay winding is coordinated to provide for the release of the armature, and thus effect closure of the alarm circuit or circuits. 10

Whereas we have described our invention by reference to specific forms thereof it will be understood that many changes and modifications may be made without departing from the spirit of the invention. 15

We claim:

1. The combination of an open flame exposed to an atmosphere which would affect the combustibility of the flame to thereby vary the temperature of the flame, means for directly engaging with and extinguishing the flame, a circuit, means in said circuit controlling the flame extinguishing means, and a thermostat controlling a break point in said circuit, said thermostat being exposed directly to the heat from the flame 25 and operable upon a lowering of the temperature of the flame to control the circuit for operating the flame extinguishing means, whereby said flame extinguishing means engages with and extinguishes the flame. 30

2. The combination of a circuit, temperature responsive circuit closing devices in said circuit directly responsive to flame temperature, one of said circuit closing devices being normally open and the other of said circuit closing devices being normally closed, a flame extinguishing means for extinguishing a flame by direct engagement therewith, and means in said circuit responsive to the operation of either of the circuit closing devices for operating the flame extinguishing 40 means.

3. The combination of an operating circuit, a flame snuffing device, means in said circuit for controlling the operation of the flame snuffing device, a thermostat in said circuit exposed to the heat of a flame which is responsive to a lowering of the temperature of the flame for operating said last named means to thereby extinguish the flame. 45

4. The combination of a signal, a flame snuffing device, an electric circuit for controlling the signal, means in said electric circuit for controlling the operation of the flame snuffing device, and thermostat means exposed to the direct action of the heat emanating from said flame and controlling said last named means for operating the signal and operating the flame snuffing device to extinguish the flame upon a variation in the temperature of the flame. 50
